CONTROL MECHANISM FOR CENTRIFUGAL CHARGING VALVES

Bradley G. Cox, Saginaw, Mich., assignor to
 Baker Perkins Inc., Saginaw, Mich., a corpora-
 tion of New York

Application September 5, 1947, Serial No. 772,367

2 Claims. (Cl. 210—63)

1

This invention relates to charging valves for centrifugals and to a control therefor, the principal object being the provision of a charging valve having certain new and useful characteristics and a novel control for the valve for closing it when it appears imminent that an excessive charge is being discharged through the charging valve of the centrifugal.

Objects of the invention include the provision of a charging valve particularly adaptable for use in connection with centrifugals so constructed and arranged as to minimize, or completely prevent, the possibility of leakage from the valve from dripping or flowing into the centrifugal; the provision of a valve of the type described providing means for receiving and holding liquid dripping or otherwise escaping between the relatively movable surfaces of the valve when in the closed position; and the provision of a valve of the type described including a movable member providing a drip collecting pocket when in closed position.

Further objects of the invention include control means for a valve of the type described including a member adapted to project into the interior of the centrifugal basket while the valve is open and adapted to be contacted and moved by an excessive charge in the centrifugal basket, thereby to actuate the valve operating mechanism to move the valve to closed position; the provision of a construction above described in which that part of the mechanism which projects into the centrifugal basket is withdrawn from the basket when the valve is moved to its closed position; the provision of a construction as above described in which, when the said mechanism is withdrawn from the basket, it is so positioned that any drip therefrom is prevented from dripping back into the centrifugal basket; and the provision of mechanism of the type described in which the movable part of the control mechanism is positively connected to the valve mechanism for interrelated movement therewith.

The above being among the objects of the present invention the same consists in certain novel features of construction and combinations of parts to be hereinafter described with reference to the accompanying drawings, and then claimed, having the above and other objects in view.

In the accompanying drawings which illustrate a suitable embodiment of the present invention and in which like numerals refer to like parts throughout the several different views,

Figure 1 is a fragmentary, partially broken, vertical sectional view taken centrally through

2

one form of centrifugal apparatus of the type to which the present invention may be adapted, showing the valve and the control mechanism therefor of the present invention in operative relation with respect thereto;

Figure 2 is an enlarged, fragmentary, partially broken, partially sectioned view of that part of the mechanism shown in Figure 1 including the charging valve and its control mechanism, to better illustrate the same, the charging valve being shown in closed position;

Figure 3 is a still further enlarged, partially broken, partially sectioned view, taken in the same direction as the views in Figures 1 and 2, but in greater detail showing the charging valve itself, in closed position;

Figure 4 is a fragmentary sectional view taken on the line 4—4 of Figure 3;

Figure 5 is a view similar to Figure 2, but showing the valve in its open position, and control mechanism with its limit gauge in lowered position;

Figure 6 is a fragmentary, partially broken plan view of the valve and its control with the valve in the position illustrated in Figure 2;

Figure 7 is a view similar to Figure 6, but illustrating the valve and its control mechanism in the position shown in Figure 5, and

Figure 8 is an enlarged, partially broken, side elevational view of the control mechanism in its raised position.

Although the present invention is applicable to any type of centrifugal, and regardless of the material to be processed thereby, it is particularly applicable to centrifugals employed for use in the sugar industry. Accordingly, for the purpose of description, the centrifugal shown in the accompanying drawings is of the vertical type and will be described only in its relation to its use as a sugar centrifugal, its application to other types of machines and other uses thereby being made apparent to those skilled in the art.

Centrifugals employed in the sugar industry are usually automatically controlled in such a manner that the various phases of operations follow each other in succession, and an allotted time period is provided for each phase of operation. For instance, the charging valve is automatically opened and remains open for a predetermined period of time, upon the termination of which it closes. A time interval is provided during which no charging occurs, so as to discharge all of the syrup remaining in the centrifugal basket from the basket, then wash water is automatically introduced into the basket to

wash the syrup from the crystals therein and is turned off after a predetermined period of time; the basket continues to rotate for a predetermined time to dry the crystals of sugar in the basket, and then a pushing mechanism provided for discharging the crystals is operated to discharge the crystals and is then returned to its original position, upon which the charging valve is again opened and the above described sequence of operations is automatically repeated.

Because of variations in pressure on the liquid being charged to the centrifugal, its relative concentration, or for other reasons, there is a possibility that the layer of sugar crystals in the basket will build up at a faster rate than contemplated, and under such conditions if the charging valve is allowed to remain open its full allotment of time the centrifugal basket will overflow, either with syrup or sugar crystals, the occurrence of either of which is undesirable.

The present invention provides a safeguard from such overloading, and this is accomplished by means of a limit or thickness gage which is placed in operative position in the centrifugal basket when the charging valve is opened and is positioned to be contacted by the layer of crystals of sugar in the basket after they have built up to a predetermined maximum thickness on the screen. Upon contact with the layer of crystals the limit gage is moved to actuate an electric switch which in turn closes the charging valve so that no more syrup is discharged into the centrifugal chamber or basket.

An important feature of the invention is the withdrawal of the limit gage from within the centrifugal chamber or basket when the charging valve is closed and into such a position that any syrup dripping from the gage will not drip into the centrifugal chamber, but will be removed to a position away from the crystals in the chamber or basket.

A further feature of the present invention is the construction and arrangement of the charging valve itself which is so constructed and arranged as to prevent syrup, which leaks between the movable parts, from dripping into the basket and upon the sugar crystals, causing them to lump or coalesce.

Referring now to the accompanying drawings and particularly to Figure 1, a charging valve indicated generally at 16 and a control mechanism therefor indicated generally at 12, constructed according to the present invention, are shown in association with a sugar centrifugal. While the present invention is adapted to any suitable type or construction of centrifugal, the particular centrifugal shown by way of illustration is that shown and claimed in the copending application of Thomas Evans and the present applicant, for improvements in Centrifugals, filed September 19, 1947 and serially numbered 774,970. Briefly, it comprises a suitable framework 14 supporting on its top a driving motor 16 arranged with axis vertical and adapted to rotate a shaft 18 the lower end of which has fixed thereto a circular disk-like portion 20 constituting a stripper or pusher non-rotatably received within a centrifugal screen or basket 22, which forms the centrifugal chamber, and which is provided with a substantially closed and imperforate bottom wall 24 fixed thereto. The basket 22 is adapted to be raised or lowered by means of a piston (not shown) received in the coaxial cylinder 26 below the wall 24. A curb ring 28 is positioned at the upper end of the

basket and rotates therewith and limits the upper movement of the syrup and crystals in the basket 22 under centrifugal action during operation. The curb ring is fixed with respect to the pusher 20 or stripper 22. The basket 22 over its height is enclosed by an imperforate wall 30 arranged in outwardly spaced relation with respect thereto which receives the liquids thrown off by the basket 22 and which liquids are drained therefrom and led to a suitable point of deposit. It will be understood that after syrup has been introduced into the basket 22 through the valve 16 for a sufficient length of time to permit a desired body of crystals to be built up in the basket 22, the valve 16 is closed, the basket continues to rotate until all the liquid is discharged from the basket, wash water is introduced into the basket 22 to wash the syrup from the crystals, and after this water has been thrown off and the basket has continued to rotate for a sufficient length of time to dry the crystals, the piston in the cylinder 26 is actuated to lower the basket 22 which action lifts the curb ring 28 and pusher 20 relative to the basket 22 so as to force the crystals off over the top of the basket, after which the basket is raised to re-establish its normal position with respect to the pusher 20 and curb ring 28, the charging valve then opened and the operations repeated.

The valve 16 is connected to a supply duct 34 which leads to a suitable supply of syrup which is to be centrifuged. As best brought out in Figs. 3 and 4 the valve 16 comprises a hollow body 36, open at both ends and preferably of square cross-sectional configuration as shown. It is provided with a surrounding outwardly directed flange 38 serving as a mounting therefor inasmuch as it is suitably secured to a bracket 40 fixed to the cover 42 of the centrifugal. The forward end of the body 36 is curved to conform to a part of the cylindrical surface having a horizontal axis passing through the body 36 midway of its upper and lower walls and is closed by a swinging shutter or valve plate 46. The valve plate 46 is wider than the body 36, as brought out in Fig. 4, and integrally secured to each opposite end edge thereof is a radially inwardly extending side plate 48. Each plate 48, on the axis of rotation of the valve plate 46, is provided with an axially inwardly extending pivot pin 50 which is rotatably received in a block 52 located on the corresponding side of the body 36 and longitudinally adjustably secured to an outwardly projecting flange 54 on the body by means of a pair of screws 56 passing through slots 58 in the flanges 54. To control this adjustment, a screw 62 is projected through an extension 64 of the flange 38 and threads into said block.

As best brought out in Figure 3, it will be noted that the valve plate 46 is of greater arcuate length than the curved outer end of the body 36. When the valve plate 46 is in closed position, its lower end projects a material distance rearwardly beyond a vertical plane including the axes of the pins 50 so that, as illustrated in Figure 3, a drip collecting pocket is formed in the lower portion of the valve plate 46 between the side plates 48. The purpose forming this pocket is to provide a means for catching and storing any leakage of liquid between the nozzle body 36 and the valve plate 46, and so that, should such leakage develop, it will form a pool such as indicated at 66 in Figure 3 in the bottom portion of the plate 46. When the valve 16 is opened any liquid in the pocket 66 will be dis-

charged either onto the curb ring 28 or into the basket 22.

The reason why it is the desire to prevent any dripping from the nozzle 10 when in closed position is that, should syrup drip from the nozzle into the basket of the centrifugal after the washing operation on the crystals has been completed and before the crystals have been discharged from the basket, such drippings of syrup would cause the crystals wet thereby to coalesce with one another and to form undesirable lumps in the crystalline sugar. In this connection it may be also noted in Figure 3 that the valve plate 46 in closely adjacent relationship with respect to its lower edge is provided with a transverse flange or baffle 70, extending the full width thereof, so that should the pool 66 overflow the lower edge of the valve plate 46 and tend to flow to the lowermost point of the valve plate, the baffle 70 will intercept such flow and cause it to drip from the valve plate before it reaches such lower point. The purpose of this is that, as brought out in Figure 3, the valve 10 is so positioned with respect to the curb ring 28 that should any such overflow of the fluid 66 occur and be drained from the valve plate by the baffle 70, such drainage, as indicated in Figure 3, will drain upon the curb ring 28 and not into the basket 22. The curb ring 28 rotating under the conditions assumed, any such drippings fed to it will be thrown centrifugally radially outwardly and prevented from entering the basket 22.

In opening the valve 10, the valve plate 46 is rotated in a counterclockwise direction from its closed position illustrated in Figure 3 to its open position which is illustrated in Figure 5. To control the movements of the valve plate 46 a lever arm 72 is fixed at one end to one of the side plates 48. Its free end is connected to any suitable type of power means, shown by way of illustration as a piston and cylinder assembly. In such case, the free end of the lever 72 is connected by a clevis 74 and pin 76 to the outer end of the piston rod 78 of a piston and cylinder assembly 80 pivotally mounted at its outer end as by means of a pin 82 to the supply duct 34 about an axis parallel to the pivotal axis of the valve plate 46.

The assembly 80 comprises a cylinder 82a within which a piston 84 is reciprocably received and fixed to the inner end of the piston rod 78. The upper or left-hand end of the cylinder 80 is closed and the lower right-hand end thereof is closed except for the opening necessary for passage of the piston rod 78 therethrough and which is sealed with respect to said piston rod. A tube 86 leads into one end of the cylinder 82 and the tube 88 leads into the opposite end, the tubes 86 and 88 leading to a solenoid operated valve indicated generally at 90 in Figure 1 having an inlet or supply pipe 92 and a discharge pipe 94. The solenoid valve 90 is of the conventional type spring pressed towards one position, preferably that in which the supply pipe 92 is placed in communication with the tube 88 and the tube 86 with the discharge duct 94, so as to move the piston 84 to valve closed position, and when energized the valve is actuated to connect the supply pipe 92 with the tube 86 and connect the tube 88 with the discharge duct 94, so as to move the valve to open position.

As previously explained, where apparatus of the type described is automatically controlled, a suitable timer mechanism is provided which acts to energize the solenoid valve 90 to open the charging valve 10 at a particular point in each cycle of operation, and after a predetermined time ele-

ment has expired deenergizes the solenoid 90 so as to close the valve 10, and that if, for some reason or other, an excessive charge tends to build up in the basket 22 before the control mechanism is actuated to close the valve 10, means are preferably provided actuated by the excessive charge in the basket 22 to close the valve 10 before the predetermined time for closing the same has expired. Broadly, this is an old idea, but the mechanism provided in accordance with the present invention is believed to be new and to involve a new principal of operation. This part of the apparatus will now be described.

In that part of the invention dealing with the control of the valve in event of excessive charge therethrough to the basket 22, it will be noted that in the specific form of the invention shown on the cover 42 opposite the valve 10 is mounted, an L-shaped bracket member 100, one leg of which lies in flat contacting relation with respect to the cover 42 to which it is suitably secured, and the other leg of which projects vertically upwardly and preferably lies in a plane parallel to a vertical plane including the axes of the valve 10 and supply duct 34, and is generally in alignment with the lever 72. The bracket 100 is provided with a slot 102 in its vertical flange, such slot extending from a point near the outer end of the bracket 100 in parallel relation to the bottom flange thereof, and at a constant width, to a point adjacent the opposite end of the bracket where it joins a vertically directed portion 104 the upper end of which is on substantially the same level as the upper edge of the horizontal portion of slot 102.

The bracket 100 mounts a carriage, the construction and mounting of which will now be described. As best brought out in Figure 8 the carriage comprises a generally U-shaped member 112, the opposite ends of which are provided with aligned and elongated sleeve portions 114 and 116, respectively. As best brought out in Figure 8, a screw 118 and a pin 120 arranged in spaced and parallel relation with respect to each other and perpendicular to the plane of the vertical flange of the bracket 100 project through the base of the carriage 112 and through the slot 102 within which each rotatably receives thereon a roller 122 of substantially the same diameter as the width of the slot 102. On the opposite side of the vertical flange of the bracket 100 is a retainer plate 124 through which the screw 118 and pin 120 project, the former receiving a nut 126 outwardly of the plate 124. A shifting member 128 for the carriage 112, shown in the form of a link 128, operatively connects the valve mechanism 10 to the carriage 112.

The link 128 is apertured for reception of the pin 120 connecting it to the carriage. The opposite end of the lever 128 is similarly formed and is pivoted to the piston rod 78 by the same pin 76 which connects the clevis 74 to the lever 72. In this manner, the carriage 112 is connected to the valve 10 for simultaneous movement therewith.

The carriage is of course supported by the rollers 122 for movement in a direction of the length of the slot 102. The link 128 is of such length that when the valve 10 is in closed position the carriage 112 is in its extreme outward position with respect to the axis of rotation of the centrifugal as shown in Figures 2 and 6, and when the valve is opened the carriage is moved toward its extreme inward position. In this last mentioned position, it will be noted that the inner

most roller 122 moves to the bottom of the vertical slot portion 104 and the outer roller 122 moves into the upper portion of this inner vertical portion of the slot, placing the carriage 112 in vertical position.

Referring again to Figure 8, it will be noted that a pin or shaft 140 extends between and is journaled in the sleeve bosses 156 and 160 of the carriage 112. That end of the shaft 140 which projects inwardly beyond the inner end of the corresponding sleeve 114 has rigidly fixed thereto a radially outwardly directed plate-like part 142 which constitutes a limit or thickness gage. The opposite end of the shaft 140 which projects beyond the outer end of the sleeve 114 has fixed thereto the hub 144 of a quadrant-shaped arm 146, the outer end of which is provided with an axially inwardly projecting portion 148 which overlies a horizontal web 150 formed between the boss 116 and the corresponding end of the carriage 112. A screw 152 threaded through the web 150 abuts the portion 148 to limit rotation of the shaft 140 in one direction. The shaft 140 is constantly urged in a direction of rotation tending to urge the portion 148 against the screw 152 by means of a coil torsion spring 154 surrounding the shaft 140 between the sleeves 114 and 146 and fixed at its opposite ends in collars 158 and 162 secured to the sleeve 114 and shaft 140 respectively. The shifting means or link 128 as shown in Fig. 5 operates, when the valve mechanism is actuated by the power means 30, to remove the gage part 142 and the carriage 112 from their normal working position within the basket 22, to their inoperative position outside the basket, as indicated in Fig. 2.

As will be observed from the various figures of the drawings, when the carriage 112 is brought to the limit of its movable position, as shown in Figs. 5 and 7, corresponding with the open position of the valve 10 and in which the carriage is arranged vertically, the gage 142 has passed downwardly below the inner edge of the curbing 28 and into the interior of the basket 22, and at such time the gage 142 projects away from the shaft 140 in a generally radially outwardly direction with respect to the axis of rotation of the basket 22. It is thus in a position to be engaged by an excessive charge in the basket 22, and, when engaged by such charge, is adapted to be moved thereby in the direction of rotation of the charge and correspondingly rotate the shaft 140 against the force of the spring 154. Rotation of this shaft is relied upon to operate the solenoid valve 30 to close the valve 10 so as to limit further discharge of material from the valve 10 into the basket 22, and this is accomplished in the following described manner.

The arm 146, as best brought out in Fig. 7, is formed as the quadrant of a circle with an included angle of approximately 90°. One end of this quadrant is cut off at an angle as at 170 so as to constitute a cam surface. A projection 172 is formed at the opposite end of the quadrant to act as a stop. The relation of the above described quadrant with respect to gage 142, when the parts are in their normal operative position with the valve 10, is illustrated in Figure 7.

A bracket 174 is mounted on the upper face of the bracket 100. It is provided with an upstanding arm 176 the upper end of which is located in transverse alignment to the arm 146 on the outer end of the shaft 140 when the carriage 112 is in its vertical position. A conventional electrical switch 178 is secured to the upper end

of the arm 176. The switch 178 is of that conventional type which is spring pressed toward closed position and is provided with a projecting actuating pin 180 which, when depressed, opens the switch. The pin 180 projects inwardly toward the axis of the shaft 140 when the carriage 112 is in its vertical inner position, as brought out in Figure 7, and the pin 180 is located in the cutaway portion of the arm 146 forming the cam 170.

The centrifugal rotates in a clockwise direction of rotation, as viewed in Figure 7, so that, should the contents of the basket 22, and particularly the crystals of sugar, build up to such a point as to contact the gage 142, it will cause the outer end of the gage 142 to move in the direction of rotation of the material in the basket 22 and correspondingly rotate the shaft 140 and arm 146 in a clockwise direction of rotation about the axis of the shaft 140, upon which movement the cam 170 of the arm 146 will contact the post 180 of switch 178 and depress it, moving the switch to open circuit position. The end of the post 180 will ride up onto the arcuate portion of the arm 146 and move the switch 178 to open circuit position.

As soon as the switch 178 is moved to open circuit position it breaks the flow of current to the solenoid switch 30, which then immediately moves to a position to introduce fluid under pressure to the line 38 and exhaust fluid under pressure from the line 36, thus causing actuation of the piston 34 in a direction to close the valve 10. Because of the link 28, when the valve 10 thus moves to closed position, the carriage 112 is moved to its inoperative position illustrated in Figs. 2 and 6, which withdraws the gage 142 from the basket 22 and moves it outwardly with respect to the axis of rotation of the basket beyond the inner edge of the curb ring 28, as best brought out in Fig. 6. This last feature is important in that any syrup which may have adhered to the gage 142 and associated parts of the carriage 112 might otherwise drip back into the basket 22 if the gage 142 or associated parts still projected inwardly of the inner edge of the curb ring 28. As before mentioned, such dripping of syrup would be undesirable at a time when the sugar crystals in the basket 22 were in a condition to be discharged from the basket, for the introduction of any syrup at this time would wet some of the crystals and cause them to coalesce with one another, thereby forming lumps in the final product. The curb ring 28 rotates with the basket 22 so that any drippings falling on it are thrown centrifugally outwardly away from the basket.

It might also be noted that as soon as the gage 142 is actuated under the conditions above stated to open the switch 178 and close the valve 10, the carriage 112, in moving to its normally inoperative position, disengages the arm 146 from the switch post 180, thereby returning the switch to its normally closed position.

The automatic control of such centrifugals being conventional, a diagram to illustrate the same is not believed necessary to the proper understanding of the present invention and is therefore not here shown, but is shown and described in the copending application previously identified. For the purpose of illustration, however, it may be noted that in Fig. 1 one side of the solenoid valve 30 is shown as being connected to a suitable source of current indicated at 190 and connected at its opposite side by a lead 192 with the switch 178. The opposite side of the

switch is shown as being connected by a lead 194 through a switch indicated diagrammatically at 196 with the opposite side of a solenoid valve 90. The switch 196 is shown merely as illustrative of the switch mechanism in the automatic control usually provided in automatic centrifugals for controlling the solenoid valve 90 or the equivalent, controlling the opening and closing of the charging valve.

What is claimed is:

1. In a centrifuge having a supply duct and valve and a basket, power means for opening and closing said valve, a thickness gauge operable upon engagement with a predetermined thickness of material on the wall of the basket to 15 actuate the power means in a direction to close the valve, said gauge including a rotatable shaft, a carriage supporting said shaft for rotational movement, a stationary bracket adjacent said basket and having a curved slot with substantially horizontal and vertical portions, said carriage being mounted in said slot, and a link extending between said valve and said carriage, said carriage being movable by said link between

an operative position in the vertical portion of said slot when the valve is opened and an inoperative position in the horizontal portion of said slot when the valve is closed.

2. The combination according to claim 1 further provided with a curb ring disposed above said basket, the thickness gauge when in its inoperative position being disposed above said curb ring.

BRADLEY G. COX.
